CLAIM

The ornamental design for a covered toothbrush holder, as shown and described.

DESCRIPTION

FIG. 1 is a front elevational view of a covered toothbrush holder showing our new design;

FIG. 2a is a rear elevational view thereof;

FIG. 2b is a front elevational view showing the pedestal in a bent, or wall-mounting, position;

FIG. 3 is a side view, taken from the left side of FIG. 1;

FIG. 4 is a side view, taken from the right side of FIG. 1;

FIG. 5 is a top plan view thereof; and,

FIG. 6 is a bottom plan view thereof.

The broken lines showing toothbrushes in the figures are for illustrative purposes only and form no part of our claimed invention.
